CLAIM

The ornamental design for a slideable display sign, as shown and described.

DESCRIPTION

FIG. 1 is a front elevational view of a slideable display sign showing my new design;

FIG. 2 is a front elevational view thereof, with the sliding portion in alternate position;

FIG. 3 is a side elevational view thereof, with the opposite side being a mirror image;

FIG. 4 is a rear elevational view thereof;

FIG. 5 is an end elevational view thereof, with the opposite end being a mirror image; and

FIG. 6 is a perspective view thereof.

FIG. 1

FIG. 2

FIG. 3

FIG. 4

FIG. 5

FIG. 6
